UNITED STATES PATENT OFFICE.

JONATHAN A. HUNT, OF WESTBOROUGH, MASSACHUSETTS.

DESIGN FOR A BICYCLE-SADDLE.

SPECIFICATION forming part of Design No. 27,813, dated November 2, 1897.

Application filed August 21, 1897. Serial No. 649,083. Term of patent 7 years.

To all whom it may concern:

Be it known that I, JONATHAN A. HUNT, a citizen of the United States, residing at Westborough, in the county of Worcester and

5 State of Massachusetts, have invented and produced a new and original Design for Bicycle-Saddles, of which the following is a specification, reference being had to the accompanying drawings, forming a part thereof.

10 My invention relates to a bicycle-saddle; and it consists in a new and original design for a saddle, as will be hereinafter fully described.

Referring to the drawings, Figure 1 is a plan view of a bicycle-saddle showing my design, 15 and Fig. 2 is a rear edge view of the same.

The leading feature of my design for a bicycle-saddle consists of a single raised or elevated cushion-surface extending across the top of the saddle to form the seat, and a recess or depression in the front part of this

raised surface and a recess or depression in the rear part or edge of the raised surface, said two depressions in the raised surface or seat not being connected.

In the accompanying drawings is a bicycle-saddle showing my design of the raised surface or seat 1. The seat 1 is a single cushion-surface which extends across the top of the saddle and has the longitudinal or elongated recess or depression 2 therein at the front 25 part thereof and the recess or depression 3 therein at the rear part or edge thereof. Said two depressions 2 and 3 are not connected.

What I claim is--

The design for a bicycle-saddle, substantially as shown and described.

J. A. HUNT.
